United States Patent Office

Des. 188,345
Patented July 5, 1960

188,345

VIBRATING REED INSTRUMENT OR SIMILAR ARTICLE

Frederick E. Lombard, Dublin, Pa., assignor to James G. Biddle Company, Philadelphia, Pa., a corporation of Pennsylvania

Filed Nov. 16, 1959, Ser. No. 58,360

Term of patent 14 years

(Cl. D52—1)

FIG.1.

FIG.3.

FIG.2.

FIG.4.

Fig. 1 is a perspective view of the vibrating reed instrument or similar article, showing my new design;

Fig. 2 is a front elevational view thereof;

Fig. 3 is a top plan view thereof, and

Fig. 4 is a side elevational view thereof.

The rear of the vibrating reed instrument casing is plain in appearance.

The essential features of my design reside in those portions shown in full lines.

I claim:

The ornamental design for a vibrating reed instrument or similar article, as shown and described.
